(57) **CLAIM**

The ornamental design for an information handling system,
as shown and described.

DESCRIPTION

FIG. 1 is an angled right frontal perspective view of the
information handling system housing comprising the present
invention;

FIG. 2 is a front elevation view thereof;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines are shown in the views for illustrative
purposes only and form no part of the claimed design.
